UNITED STATES PATENT OFFICE

DANIEL H. CALDEMAYER, OF EVANSVILLE, INDIANA

FOLDING DAVENPORT BED

Application filed December 31, 1927. Serial No. 243,911.

The present invention has for its object the provision of improvements on the folding davenport bed set forth in my Patent No. 1,591,608 dated July 6, 1926.

The present invention employs links for the swing-over bed bottom section, and springs, substantially like those set forth in my patent.

The foldable legs for the swing-over bed bottom section are, however, operatively connected to the extended ends of a pair of the links or levers by connected bars and are thereby automatically opened out or lowered from their folded position when the swing-over bed bottom section is opened up or extended and are braced by said connecting bars when said section is fully extended, thereby overcoming a defect in respect to the legs of my patented construction. When the swing-over bed bottom section is closed the connecting bars are operated by the links or levers to automatically fold the legs.

Another, and the principal, improvement over the construction of Patent No. 1,591,608 comprises a main bed bottom section which is mounted for automatic bodily elevation from its normal position, thereby enabling it and the swing-over bed bottom section normally to assume a relatively low position when the piece of furniture is arranged with the bed bottom sections stacked on top of each other for use as a davenport.

As hereinafter described, the construction involved in this part of the invention embraces a bail whose cranks or arms are connected to the pair of spring-actuated links or levers and which mounts the main bed bottom section.

When the swing-over bed bottom section is stacked on the main bed bottom section the main bed bottom section is in lowered position, the bail then being turned downward, but when the swing-over section is opened out to transform the davenport into a bed, the main bed bottom section is bodily elevated by a swinging movement so that it will be at a suitable height from the floor and also on substantially the same level as the swing-over section when the latter is supported by the floor. When thus

arranged, the cranks of the bail are disposed in substantially upright position or on "dead center" and as the main bed bottom section has stops which then engage the frame of the piece of furniture, said section is firmly held, is level, and is substantially aligned with the swing-over bed bottom section, thus affording a comfortable bed.

Another advantage residing in the improved mounting for the main bed bottom section is that when in normal position, as when the piece of furniture is arranged as a couch or davenport, the two sections are located at relatively low height as compared with the sections of davenport beds of which I have knowledge so that the upholstered front which is carried by the swing-over section does not possess the very considerable height so noticeable in davenport beds and which reveals them to be a davenport bed instead of a regular davenport; consequently, in my piece of furniture there is little to suggest that it is a davenport bed and this renders it more desirable, particularly where the user has to have the piece of furniture in a living room or parlor.

A practical embodiment of the invention is hereinafter described and is illustrated in the accompanying drawings in which:

Fig. 1 is a cross section, the piece of furniture being arranged as a davenport or couch;

Fig. 2 is a similar view showing the piece of furniture arranged as a bed;

Fig. 3 is a similar view showing the davenport bed in partly opened condition to illustrate the manner in which the main bed bottom tilts during its bodily shifting movement to elevated position;

Fig. 4 is a plan view, broken away, showing the davenport fully opened out for use as a bed;

Fig. 5 is a front elevation of the davenport bed when closed, illustrating its relatively low height at the front;

Fig. 6 is a detail perspective view, parts being broken away, showing the main bed bottom section in fully elevated position; and

Fig. 7 is a detail perspective of the bail. 100

The davenport comprises, generally stated, an upholstered section 1 of conventional form having backs and sides, and a frame 2 provided with legs 3.

The main bed bottom appears at 4 and the swing-over bed bottom is shown at 5.

The main bed bottom 4, unlike the main bed bottom of my Patent No. 1,591,608, is mounted in a novel manner for bodily movement from a relatively low normal position to an elevated position when the davenport is opened out for use as a bed, thus obtaining those advantages over my patented construction which have been heretofore set forth.

The bed bottom section 4 is carried by the offset part of a bail 6 which appears in detail in Fig. 7. For that purpose, the bottom 4 has depending plates 7 provided with openings 8 serving as bearings for the bail. Bridging the frame pieces 2 are angle iron bars 9 at the opposite ends of the couch, said bars being secured to the frame 2 at 10. These bars 9 are provided with depending plates or legs 11 in which the crank ends 12 of the bail 6 are journalled or rockably mounted.

The bottom 4 is provided with depending L-shaped stops 13 whose horizontal parts are adapted to engage the undersides of the horizontal webs of the bars 9 when the davenport is opened out to serve as a bed, as shown in Fig. 2, thereby rendering the bottom 4 rigid when used as a bed section.

Furthermore, when the bottom 4 is thus disposed, the crank arms 12 are arranged in substantially vertical position as shown by dotted lines in Fig. 2 so that the weight on the section 4 is sustained when the bail 6 is on "dead center," so to speak, thus preventing the weight on the bottom 4 from causing it to descend or to elevate the bottom of section 5.

By mounting the bottom 4 in the manner previously described, it is permitted normally to assume the relatively low position shown in Fig. 1 when the davenport is used as such. This has the decided advantage of enabling the bottom 5 to assume a much lower position when arranged as in Fig. 1 so that the upholstered or finished front bar 14 may be arranged in relatively low position and require only relatively slight depth from its upper to its lower edges. Consequently, when the davenport is in its normal, closed, condition as shown in Figs. 1 and 5, there is not that vertical depth of the finishing bar or front of the davenport presented to the eye of the observer which so commonly exists in folding davenport beds and which discloses the fact that the article of furniture is a convertible bed.

On the other hand, the appearance of my davenport is such that it does not hint that it is, in fact, a couch or davenport but gives the impression that it is a regular davenport.

The "swing-over" system of links or levers for the bed bottom section 5 is substantially the same as those appearing in my Patent No. 1,591,608 and acts in substantially the same manner in respect to said section 5. 70

The relationship of these links or levers to the bed bottom section 4 is, however, different from the disclosures of my aforesaid patent and, in addition, one of the pairs of links or levers is utilized to automatically raise or 75 lower the supporting legs for the section 5, new combinations being involved in these improvements.

The links or levers appear at 15 and 16, the former being secured to the cranks 12 of 80 bail 6 at 17 and to the bed bottom section 5 at 18. The links or levers 16 are pivoted to the bars 9 at 19 and to the section 5 at 20.

Springs 21 which are connected at 22 to the links or levers 15 and to the bars 9 at 23, act 85 in the general manner described in my patent, in respect to the parts. These springs come into play and relieve the operator of a greater part of the work of raising the section 5 from the closed position shown in 90 Fig. 1. When the parts assume the position about as shown in Fig. 3, the springs are substantially out of tension as they have then contracted due to the different positions of the parts. As the section 5 is pulled downwardly by the operator to bring it into the position shown in Fig. 2, the springs are 95 extended and when the bed is fully opened they are under tension but are not sufficiently tensioned to overcome the weight of the section 5 and parts carried thereby. 100

When the operator begins to lift the outer part of the section 5 as the first step toward closing the bed, the springs 21 exert a lifting action to relieve the operator of the work of raising the section 5 until the parts are in about the position shown in Fig. 3. Then, by pushing on the section 5, it is swung back and easily closed. 105

The links or levers 15, being secured to the cranks 12 of the bail 6, when the section 5 is opened out, the section 4 is bodily shifted from the horizontal, lowered, position shown in Fig. 1, first to the tilted position shown in Fig. 3, due to the mounting of the section 4 110 on bail 6, and finally is completely raised to the position appearing in Fig. 2 when the section 5 is fully extended. The section 4 is then horizontally arranged in substantial alinement with the section 5, the cranks 12 115 are in "dead center" position, as shown by dotted lines in Fig. 2, and the stops 13 have their horizontal parts in engagement with the undersides of the horizontal webs of the bars 9. This insures that the section 4 120 be retained in rigid and non-tiltable position while the bed is extended. 125

When the section 5 is raised, as before described, a reversal of the movement of the section 4 occurs, such section being tilted as 130

it is bodily lowered and, finally, being brought to the lowered horizontal position shown in Fig. 1.

The legs 24 are pivoted at 25 to the section 5 and are connected by connecting bars 26 to the extended ends 27 of the levers 16 by pivots 28. These sections bring about the automatic lowering of the legs for the purpose of supporting the section 5 when it is extended, as shown in Fig. 2, and the folding of the legs when the section 5 is swung over as shown in Fig. 1.

What I claim is:

1. In a folding davenport bed, the combination with a bed frame, and a main bed bottom section, of means mounting said main section on said bed frame for bodily raising and lowering and tilting, a supplemental swing-over bed bottom section, means mounting said supplemental swing-over section on said bed frame so that said swing-over section is adapted to be superposed on said main section when the latter is in lowered position, or, to be extended horizontally in relation to said main section when the latter is in raised position, means operated by the supplemental swing-over bed bottom section whereby the main bed bottom section is bodily raised or lowered and tilted, and means on the bed frame and main bottom section, respectively, adapted to automatically adjust and retain the main section in horizontal position when it is raised and tilted, on the extension of the swing-over section to horizontal position.

2. In a folding davenport bed, the combination with a bed frame, a main bed bottom section, and cranks stationarily mounted on said bed frame and connected to said main section which mount said main section so that it may be bodily tilted and raised or lowered, of a supplemental swing-over bed bottom section movably mounted in relation to the main section and adapted to be superposed on said main section when the latter is in lowered position, or, to be extended horizontally in relation to said main section when the latter is in raised position, links connecting the swing-over section and the main section which bring the cranks to "dead center" relationship to the main section when the latter is raised, thereby supporting said main section, and means additional to the cranks and links adapted to automatically adjust and lock the supplemental swing-over section in horizontal position after it has been raised and tilted.

3. In a folding davenport bed, the combination with a bed frame, a main bed bottom section, and cranks connected to said main section which mounts said section so that it may be bodily tilted and raised or lowered, of a supplemental swing-over bed bottom section movably mounted in relation to the main section and adapted to be superposed

on said main section when the latter is in lowered position, or, to be extended horizontally in relation to said main section when the latter is in raised position, links connecting the supplemental swing-over section and the main section which bring the cranks to "dead center" relationship to the main section when the latter is raised, thereby supporting said main section, and stops respectively on the main section and frame of the bed and additional to the aforesaid elements, adapted for locking the main section in horizontal position when the cranks are on "dead center".

4. In a folding davenport bed, the combination with a main bed bottom section, and cranks connected to said main section which mount said section so that it may be bodily tilted and raised or lowered, of a supplemental swing-over bed bottom section movably mounted in relation to the main section and adapted to be superposed on said main section when the latter is in lowered position, or, to be extended horizontally in relation to said main section when the latter is in raised position, links connecting the supplemental swing-over section and the main section which bring the cranks to "dead center" relationship to the main section when the latter is raised, thereby supporting said main section, horizontal angle bars carried by the bed, and stops carried by the main section, said stops being adapted to engage the under sides of the angle bars and to automatically adjust the main section in horizontal position and hold it against tilting when the cranks are on "dead center".

5. In a folding davenport bed, the combination with a main bed bottom section, of cranks directly connected to a fixed point on said section in the general central region thereof, whereby the main section may be bodily raised and lowered and tilted, a supplemental bed bottom section movably mounted in relation to the main section and adapted to be superposed on said main section when the latter is in lowered position, or, to be extended horizontally in relation to said main section when the latter is in raised position, means connecting the supplemental section to the cranks whereby said cranks are operated by the movements of the supplemental section, and co-operating means additional to the cranks and to the mounting means for the supplemental section, and carried by the respective sections, for automatically adjusting the main section into general horizontal position from its tilted position when the supplemental section is in extended position.

6. In a folding davenport bed, the combination with a main bed bottom section, of a supplemental walk-over bed bottom section, a bed frame, means mounting the main section intermediate its front and rear on the bed frame so that it may tilt, means mounting the

supplemental walk-over section on the bed frame so that it may fold on the main section without turning over, and means additional to the mounting means aforesaid and respectively carried by the main section and the frame, such means being normally disengaged when the sections are folded and adapted to engage when the main section is raised and tilted and thereby to automatically effect adjustment of the main section into horizontal position and to lock it in that position.

7. In a folding davenport bed, the combination with a main bed bottom section, of a supplemental walk-over bed bottom section, a bed frame, means mounting the main section intermediate its front and rear on the bed frame so that it may tilt, means mounting the supplemental walk-over section on the bed frame so that it may fold on the main section without turning over, and combined adjusting and locking means carried by the main section on opposite sides of the tilttable mounting therefor adapted to engage the bed frame and adjust the main section into horizontal position and to lock it when said main section is raised and tilted.

8. In a folding couch, the combination of a stationary main frame, an upper folding bed bottom section connected to said frame and movable from normal position over the area of the frame to an extended position adjacent one side of the frame, a lower bed bottom section located under the folding section when the latter is in normal position, lifting means cooperating with a part of said lower section at a point intermediate opposite side portions of said section so that said lower section is approximately balanced on said lifting means, for automatically elevating the lower section into position substantially coplanar with the folding section when the latter is extended and as an incident to the movement of said folding section to extended position, and spaced stops on said frame, located respectively on opposite sides of said lifting means for limiting upward movement of the lower section and serving to maintain the latter in substantially horizontal position.

In testimony whereof I affix my signature.

DANIEL H. CALDEMEYER.
